O. C. GOERZ

METHOD OF ATOMIZING FUEL OILS

Filed March 25, 1921

Testimony:
Oscar C. Goerz
C. P. Goepel
Attorney.

UNITED STATES PATENT OFFICE.

OSCAR C. GOERIZ, OF NEW YORK, N. Y.

METHOD OF ATOMIZING FUEL OILS.

Application filed March 25, 1921. Serial No. 455,551.

To all whom it may concern:

Be it known that I, OSCAR C. GOERIZ, a citizen of the German Republic, and resident of the borough of Manhattan, city, county, and State of New York, have invented certain new and useful Improvements in Methods of Atomizing Fuel Oils, of which the following is a specification.

This invention relates to an improved method of atomizing fuel oils, and has for its primary object to provide a simple, inexpensive and highly efficient method for securing complete atomization of relatively heavy fuel oils without liability of premature decomposition or carburization and which will produce a smokeless flame of substantially constant and unvarying character.

It is the purpose of my present invention to provide a method of atomizing fuel oils wherein there is no steam loss whatever and in which the oil is atomized only at the instant of its egress from the burner tip and not prior thereto. In attaining this result instead of using steam from the engine boiler, I supply to the fuel oil, water under pressure which is superheated above 212° F. and becomes thoroughly mixed with the oil. The oil is also heated above 212° F. so as to facilitate its atomization. By the maintenance of relatively high pressure in the oil and water pipe lines, the vaporization of the water is prevented and it remains in a superheated fluid condition intimately admixed with the oil. When the mixture of oil and superheated water issues from the burner, its sudden reduction to atmospheric pressure causes the instant conversion of the superheated water into steam. This steam being in intimate association with the oil, in expanding breaks up the oil and effects the perfect atomization thereof. Such perfect atomization results in easy ignition and complete combustion of the fuel.

It is further the object and purpose of my invention to provide a method of atomizing heavy fuel oils as above characterized which may readily be adapted at nominal cost for use in steamship boiler furnaces, industrial furnace installations and for various other analogous purposes. My improved method is particularly advantageous in those cases where the water available for the production of the atomized steam is not chemically pure.

With the above and other objects in view, the present invention consists in the im-

proved method to be presently described in detail and hereinafter particularly defined in the appended claim.

In the drawings wherein I have illustrated several types of apparatus by means of which the present method may be successfully practiced:

Figure 1 is a diagrammatic view showing one embodiment of apparatus for effecting the atomization of fuel oils;

Figure 2 is a similar view showing another form of apparatus which may be employed;

Figure 3 is an enlarged sectional view through one of the burner nozzles illustrating the manner in which the fuel oil is vaporized.

Referring in detail to the drawing and more particularly to Fig. 1 thereof, 5 designates an oil tank which may be of any required capacity and from which the oil is supplied by the pump 6 through the pipe line 7 to the burners 8, of which any desired number may be provided in accordance with the requirements of the particular case. In the pipe line 7 a heater 9 of any suitable form is interposed and serves to heat the fuel oil in its passage to the burner nozzles so that its atomization or vaporization will be facilitated. The pipe line 7 is also provided with a thermometer 10 whereby the temperature of the oil may be ascertained and controlled by the proper regulation of heater 9.

From a tank 11 water is delivered under pressure through the medium of a pump 12 into the pipe line 13. This water is heated by a heater indicated at 14, and the temperature of the water may be ascertained from the thermometer 15. The branch pipe lines 16 extending from the main pipe line 13 are connected to the branch pipes from the oil pipe line 7, in advance of the burner tips 8. Each of the burners is provided with a valve 17 so that the supply of oil can be regulated and controlled and the water pipe lines 16 are also provided with the valves 18 so that the supply of heated water to the burner pipes can likewise be regulated.

The water which may be more or less pure, as for instance sea-water, is heated in its passage through the pipe 13 to a temperature above 212° F. or the boiling point. The water however being under pressure greater than atmospheric will not vaporize or be converted into steam. This superheated water is supplied in proper regulated quantities

to the burners and becomes intimately admixed with the heated fuel oil. The burners 8 may be of any approved mechanical construction which will result in an intimate mixture of the oil and water before it issues from the burner tip. It is also not essential that the water pressure shall be constant, as it may vary between certain limits. However, the water pressure is maintained preferably greater than the oil pressure, the latter being controlled or throttled by the valve 17 or by a suitable form of needle valve which may constitute part of the burner. Automatic valves of various types might also be provided for this purpose. The variation in the water pressure does not result in any perceptible alteration in the character of the flame and this pressure can be easily controlled by the proper operation of the pump. The oil pipe line and the water pipe line are each provided with a pressure gauge, indicated at 25 and 26 respectively so that the requisite pressures in these pipe lines may be maintained.

As shown in Figure 3 of the drawings, immediately upon the discharge of the mixture of oil and water from the burner tip, owing to the reduction to atmospheric pressure, the superheated water will be converted into steam. This steam expanding breaks up and finely atomizes the heated fuel oil and perfect atomization occurs instantaneously at the burner tip. It will be understood that owing to the maintained pressure upon the water and oil, there is no gasification of the oil within the body of the burner so that decomposition and carburization cannot occur therein. Due to the complete and perfect atomization of the fuel oil, all combustible products will be completely consumed, therefore resulting in an entire absence of smoke which it has heretofore been extremely difficult to eliminate in those oil firing systems which depend upon the atomization of the oil by mechanical means. Further, by means of my present invention, any type of burner may be employed and a flat flame can be produced in contradistinction to the conical flame of the burner having mechanical atomizing means.

In Figure 2 of the drawings I have shown a slightly modified form of apparatus wherein the outlet pipe 20 from the water tank 19 extends through the body of oil contained in the tank 21. This pipe is equipped with a suitable control valve 22 and the end or nozzle thereof extends into the intake pipe 23 of the oil pump 24 which is connected to the tank 21. Thus in this construction it is seen that a single pump is used for placing the oil and water under pressure. The remaining parts of the apparatus are similar to those above described. It is quite immaterial at what point in the system the water is mixed with the oil and it will therefore

be apparent that various other types of apparatus might be utilized for carrying out my improved method than those above referred to. While the water used in carrying out the method above described is preferably as pure as possible, a certain degree of salinity, as in sea-water, or of alkalinity, as in water obtained from wells in oil fields, is not objectionable, and will not prevent the advantageous use of the present invention. 75

In Figure 3 of the drawings I have shown the burner tip having one or more outlet orifices 8'. In the burner chamber as indicated at A, the mixture of oil and water is under a pressure greater than atmospheric and is in fluid condition, no gas forming in this chamber, although the temperature is above 212° F. When, however, the mixture issues from the orifices 8' and the pressure is reduced to atmospheric, the superheated water is instantly vaporized and converted into steam as indicated at B. This steam expands in all directions and breaks up the heated fuel oil into exceedingly minute particles as at C, or in other words, very thoroughly atomizes the oil so that complete and instantaneous combustion occurs and all of the fuel products are consumed. 90

Preferably the oil is likewise heated above 212° F. so that the temperature of the water will not be lowered below the boiling point when the water and oil are mixed together. However, if the water is heated to a relatively high degree, say 230 or 240° F., then the oil need not be heated above the boiling point. 95

From the foregoing description considered in connection with the accompanying drawings, my improved method of atomizing fuel oils and the several described embodiments of apparatus for performing the method will be clearly understood. In view of the simplicity of the required apparatus it is apparent that this method can be advantageously utilized in connection with steam boiler furnaces of various types employed for industrial or other purposes. It may likewise be used in connection with furnaces other than boiler furnaces and in numerous analogous installations where high temperatures are required with economy in fuel consumption. 110

While I have herein referred to a satisfactory and practical embodiment of my invention, it will nevertheless be understood that the same is susceptible of many modifications and I accordingly reserve the privilege of adopting such legitimate changes as may be fairly embodied within the spirit and scope of the invention as claimed. 120

I claim:

The method of atomizing fuel oils, which consists in mixing together oil and water heated to substantially the boiling point 125

of water within a closed container under pressure greater than that of the atmosphere, discharging to the atmosphere the mixture of oil and heated water while under a pressure higher than that of the atmosphere, and converting, as it is discharged into the atmosphere, the heated water into steam by the difference of pressures between it and that of the atmosphere, whereby ex-

plosive effects produced by the expansion of 10 the heated water into steam, atomizes the oil in intimate association with the heated water.

In testimony that I claim the foregoing as my invention, I have signed my name here- 15 under.

OSCAR C. GOERIZ.
